UNITED STATES PATENT OFFICE.

GUSTAVE A. OVERSTROM, OF CHICAGO, ILLINOIS, ASSIGNOR TO OVERSTROM CONCENTRATOR COMPANY, OF BUTTE, MONTANA, A CORPORATION OF MONTANA.

ORE-CONCENTRATING TABLE.

SPECIFICATION forming part of Letters Patent No. 763,787, dated June 28, 1904.

Application filed July 30, 1903. Serial No. 167,532. (No model.)

To all whom it may concern:

Be it known that I, GUSTAVE A. OVERSTROM, a citizen of the United States, residing at Chicago, in the county of Cook and State of Illinois, have invented a new and useful Ore-Concentrating Table, of which the following is a specification.

This invention relates to ore-concentrating tables.

10 The object of the invention is to improve the construction of ore-concentrating tables and to render the same more efficient in operation.

A further object of the invention is to provide a construction and arrangement of ore-concentrating table wherein the feed supplied to the table is evenly distributed and wherein the finer particles of mineral values are permitted to settle to enable the same to be separated and recovered.

20 Other objects of the invention will appear more fully hereinafter.

The invention consists, substantially, in the construction, combination, location, and relative arrangement of parts, all as will be more fully hereinafter set forth, as shown in the accompanying drawings, and finally pointed out in the appended claims.

Referring to the accompanying drawings, and to the various views and reference-signs appearing thereon, Figure 1 is a view in plan of an ore-concentrating table embodying the principles of my invention. Fig. 2 is a section on the line 2-2 of Fig. 1 looking in the direction of the arrows. Fig. 3 is a detached detail view in side elevation of one of the long riffles and constructed in accordance with the principles of my invention. Fig. 4 is a view similar to Fig. 3, showing a shorter riffle employed lower down on the surface of the table or toward the tailings-discharge edge thereof and embodying the principles of my invention. Fig. 5 is a broken detail view in section on the line 5-5, Fig. 1, looking in the direction of the arrows. Figs. 6 and 7 are detached detail views similar to Figs. 3 and 4, showing modified forms of riffles embraced within the spirit and scope of my invention.

The same part is designated by the same reference-sign wherever it occurs throughout the several views.

In the art of ore-concentration it has been customary to employ concentrating-tables upon which the crushed ore is supplied along with feed-water, such table being slightly inclined transversely and receiving longitudinal reciprocations. It has also been customary to supply to the table-surface wash-water arranged to flow transversely across the surface of the table. Under these conditions of transversely-flowing feed and wash water, together with the inclination of the table in the direction of flow of the feed and wash water and longitudinal reciprocations, it will be seen that the ore-mineral values are subjected to forces acting thereon in intersecting lines, with the result that a tendency is created to carry the mineral particles in the direction of the component of these forces. In order to prevent the mineral values from being carried over the lower or tailings-discharge edge of the table along with the tailings feed and wash water and to enable or permit the mineral values to be caught and to settle down upon the table-surface, it has been customary to provide riffles upon the table-surface arranged to extend generally in the line of the reciprocatory movements imparted to the table, the riffles forming a protection against the liability of the mineral particles being carried across the surface of the table and over obstructions which permit the mineral values to settle down in the troughs formed by the riffles, and when once caught in this manner by a riffle such mineral particles are advanced by the reciprocatory movements in the direction of the length of the table, finally emerging from the troughs formed by the riffles upon a smooth portion or surface adjacent to the foot end of the table and over which wash-water flows and is finally delivered in concentrate form over the foot end of the table. In order to gradually withdraw the protection afforded by the obstructing riffles, it has been a common practice to taper the riffles in the

50

90

direction of the length thereof from the head end of the table toward the foot end, and thus enabling the transversely-flowing wash-water to gradually remove the tailings, silica, shale, 5 rock, gangue, and the like and accomplishing the concentration of the mineral values. This practice results in a form and construction of riffle which is highest or extends to a greater height above the surface of the table at the 10 head end of the table and gradually diminishing in height or tapering to the foot end of the table. This arrangement, however, has been found in practice to be open to objections. The fine mineral particles delivered 15 along with the feed of material and feed-water are carried to a considerable distance while being held in suspension in the feed-water. If, therefore, this feed-water carrying the fine mineral particles in suspension is 20 permitted to flow when delivered to the table over the empty riffle-spaces toward the tailings-discharge edge of the table, or rather over riffle-spaces filled with water, they are kept or retained in suspension from riffle to riffle 25 without being permitted to settle down sufficiently to be caught by the riffle by reason of the agitation of the water, due largely to the reciprocatory movements of the table, such fine particles of mineral being finally dis- 30 charged, together with the dirty feed-water, over the tailings-discharge edge or side of the table nearest the head end of the table, and hence are lost. In order to avoid this source of loss, it is desirable to provide a bed of 35 silica at the feed-in end of the table, as the finer mineral particles are more readily caught by a loose bed of silica and are permitted to settle more quickly to such bed of silica, and, moreover, the flow of the dirty water over a 40 bed of silica is more even and more free from agitation than is the case of such water flowing over empty riffle-spaces, thereby allowing the mineral particles to more readily settle between the coarser particles of silica, and 45 hence out of danger of being maintained in suspension in the water or of being washed or carried over the lower side or edge of the table along with the tailings or dirty feed-water. However, with a rifled table where- 50 in the riffles are of greatest height at the feed-in end of the table it is impossible to secure an efficient spreading out of the bed of silica, and an efficient even spreading out of this bed is an exceedingly desirable object to 55 be attained. Therefore it is among the special purposes of my present invention to provide such an arrangement of riffles in an ore-concentrating table as will permit me to secure an efficient spread of the feed over the 60 table-surface at the feed-in end or head-motion end of the table. In accordance with the principles of my invention, therefore, I propose to employ riffles which are of increasing height for a portion of the length thereof

from the head end of the table toward the 65 foot end thereof, and for another portion of the length of such riffles I propose to gradually decrease the height of such riffles. In other words, I propose to employ in practical effect a riffle tapered in both directions from 70 a point intermediate the ends thereof, so that the highest point or greatest height of the riffle above the table-surface will not be at the head end of the table, but some distance 75 therefrom toward the foot end of the table. This result may be secured either by gradually tapering the riffle from such intermediate point toward both the head and foot end thereof and also by forming the riffle in steps 80 of increasing heights from the head end of the table for a portion of the length of the riffle. I do not desire, therefore, that my invention shall be limited in this respect, and when I refer to a riffle as being "tapered" I 85 desire to be understood as including thereby not only a gradual taper of the riffle, but also the step form of construction of riffle, as will be more fully hereinafter explained.

It is usual to supply the crushed ore and feed-water to a feed-box mounted upon or 90 employed in connection with the concentrating-table, the material being deposited from such feed-box upon the concentrating-table through holes or openings formed in the bottom or sides of the feed-box, an equal quantity of the feed being deposited upon the table-surface through the feed holes or openings. In order to secure the best results, therefore, a definite relation should exist between the degree of taper of the riffle at the 95 head end of the table and the number of feed holes or openings in the feed-box. For instance, if the feed-box has eight feed holes or openings it is obvious that in order to secure the desired results of an efficient spread of 100 the material over the table-surface at the head end thereof in accordance with the principles of my invention the riffles are not required to extend as high above the table-surface at a point opposite the first of the feed holes or 105 openings in the feed-box, counting from the head end of the table, as at a point opposite the second feed hole or opening, because only the amount of mineral contained in the crushed 110 ore delivered to the table through the first opening is required to be taken care of at a point opposite such first opening, whereas this amount of feed is augmented by the amount delivered to the table through the second opening, and hence the height of the riffles opposite 115 the various succeeding feed holes or openings of the feed-box must be correspondingly increased, assuming that an equal amount of feed is supplied to the table-surface through each slot or opening in the feed-box. Thus 120 if in practice the amount of feed supplied through the first feed opening or hole requires at a point opposite thereto a riffle one thirty- 125

second of an inch in height then opposite the second feed hole or opening the height of the riffle should be just double, or two thirty-seconds of an inch, and opposite the third three 5 thirty-seconds of an inch, and so on for as many feed holes or openings, counting from the head end of the table, as the feed-box may have. Therefore it is within the spirit and scope of my invention not only to taper 10 the riffles in opposite directions, but to arrange the backward taper at the feed-in end of the table in a definite relation to the feed in order to secure the best results.

In the accompanying drawings I have 15 shown an ore-concentrating table embodying in its construction features enabling me to secure the advantages above noted and wherein reference-sign A designates the feed-box and B the wash-water-supply pipe. The feed-box A 20 is located, preferably, along the upper edge of the table and in proximity to the head end C of the table, while the wash-water-supply pipe B extends along the upper edge of the table from the feed-box to the lower end D of 25 the table. The riffles are indicated generally by reference-sign E and are arranged to extend from the head end C of the table toward the foot end D thereof and in very nearly parallel relation with respect to each other. 30 I prefer to slightly flare or separate the riffles at the head end of the table, so as to secure a greater space between the riffles at this point to enable the feed to be more evenly spread out when received upon the table and 35 over a more extensive surface or area. Each riffle is provided with a double taper, the tapered portion of each riffle being indicated by reference-signs F and G, the tapered surface G beginning at the point H and extending 40 therefrom to the extreme head end of the riffle, while the taper F begins at the point J and extends to the extreme foot end of the riffle in the forms of my invention shown in Figs. 1, 2, 3, and 4, leaving a portion of the 45 riffle between the points H and J of equal height above the surface of the table. If desired, however, and included within the spirit and scope of my invention, the oppositely-tapering surfaces F' G' of the riffle E' may 50 meet in an apex H', thereby omitting the portion extending between the points H and J. This form of riffle is illustrated in Fig. 6. In accordance with the spirit and scope of my 55 invention the degree of taper of the surface G of each riffle, especially that portion of the riffles lying directly opposite the feed-box, should bear a definite relation to the feed, as above explained. For instance, in the particular case illustrated, to which, however, 60 my invention is not to be limited or restricted, the feed-box is provided with eight feed openings or holes marked, respectively, a, b, c, d, e, f, g, and h, and since an equal amount of material is fed to the table-surface through each

of these feed holes or openings it will be apparent that the portions of the riffles lying directly opposite the feed-opening a will be required to take care of only the amount of feed supplied through the feed hole or opening a. Therefore at this point the riffles 70 should be of the least height above the table-surface. The same amount of feed is supplied to the table through the opening b as through the opening a. Therefore to take care of this additional amount of feed the 75 portion of the riffles lying directly opposite feed hole or opening b should be of greater height than the portions of the riffles lying opposite the feed hole or opening a. If, therefore, the riffles are one thirty-second of 80 an inch high opposite feed-hole a, they should be two thirty-seconds of an inch high opposite hole b, three thirty-seconds of an inch high opposite feed-hole c, and so on for as many feed holes or openings as are provided in the 85 feed-box. As above explained, this same idea may be accomplished in providing the riffles with steps. In Fig. 7 I have shown a rifle E' having the steps a' b' c' d' e' f' g' h' instead of tapering the riffles; but, as above 90 explained, this form of riffle is designed to be included within the generic expression of "taper" in describing and claiming this feature of my invention.

At their foot ends the riffles terminate, preferably, at right angles to a line transverse of the table and upon a smooth or unriffled portion or surface M of the table, (see Fig. 1,) the concentrates delivering over the linoleum apron N at the extreme foot end of the table, 100 any middlings that may be produced being delivered over a short raised rib A', arranged at the lower side or edge of the table at its extreme lower corner or between the points marked O and P, while the tailings, sand, 105 silica, or the like are delivered over the tailings-discharge edge K of the table between the points marked O and Q.

So far as the work of spreading the feed over the table-surface is concerned only the 110 portion of the riffles lying directly opposite to the feed-box need be tapered backwardly or toward the head end of the table, and in Fig. 1 I have indicated by the dotted lines R and S the line of the beginning of the backward as 115 well as the line of the beginning of the forward taper of the riffles.

Reciprocations may be imparted to the table in any suitable or convenient manner. I have indicated at W an operative mechanism 120 for accomplishing this result; but I do not desire to be limited or restricted to the specific construction shown, as any form of head-motion mechanism may be employed.

The operation of an ore-concentrating table 125 embodying the principles of my invention will be readily understood; but for the sake of clearness I will briefly set forth the same.

The feed, along with the feed-water, is supplied to the feed-box and is delivered thence upon the table-surface at its upper corner through the feed holes or openings *a b c*, &c., 5 through the feed-box. The material becomes quickly spread out evenly over the surface of the table at the head end of the table, and under the combined influence of the reciprocatory movements imparted to the table and 10 the transversely-flowing feed and wash water and inclination of the table the work of separation commences. The mineral values being heavier than the silica, gangue, shale, rock, and the like settle down through the bed or 15 mass of sand, silica, or the like and in between the riffles, and any of the finer mineral particles held in suspension in the feed-water are permitted to settle down to the surface of the bed of silica by reason of the fact that 20 the water is not so violently agitated when flowing over such bed and over an extended area thereof produced by the backwardly-tapering portions *G* of the riffles, and hence I avoid the danger of such finer particles of mineral 25 being carried or washed over the tailings-discharge edge of the table along with the dirty feed-water, sufficient opportunity being given to enable or permit such finer mineral particles to settle down. As the operation 30 of the machine continues, the mineral values, along with a portion of the sand, silica, rock, and the like, are advanced in the direction of the length of the riffles and under the protection afforded by the riffles as obstructions until 35 they gain the table-surface below or toward the foot end of the table from the feed-box. Here the wash-water plays transversely across the table-surface, and hence by reason of the gradual withdrawal of the protection afforded by the riffles, due to the forwardly-tapering surfaces *F* of the riffles, a gradual and eventually a complete separation of the mineral values from the dirt, silica, and the like is effected, the latter being washed transversely 40 across the table and over the tailings-discharge edge of the table with the wash-water, the mineral values being finally delivered upon the smooth unriffled surface *M* of the table, where the final separation due to 45 the action of the wash-water is accomplished, the concentrates being finally delivered over the foot end *D* of the table.

From the foregoing description it will be seen that I provide an exceedingly simple and 55 efficient construction of ore-concentrating table wherein an even distribution of the feed over a wide area of table-surface at a point where the feed is delivered to the table is effected and wherein every opportunity is permitted the mineral values held in suspension in the feed-water or otherwise to settle or 60 gravitate to the table-surface or to the protection of the riffles or the coarser particles of sand, rock, or the like.

I desire it to be understood that many variations and changes in the details of construction and arrangement would readily occur to persons skilled in the art and still fall within the spirit and scope of my invention. I do not desire, therefore, to be limited or restricted to the exact details shown and described; but,

Having now set forth the object and nature of my invention and various constructions embodying the principles thereof, what I claim as new and useful and of my own invention, and desire to secure by Letters Patent, is—

1. The combination with an ore-concentrating table and a feed-box, of riffles arranged on the upper surface of the table, that portion of the riffles lying opposite to and to an extent equal to the length of the feed-box increasing in height from the head end toward the foot end thereof, as and for the purpose set forth. 80

2. The combination with an ore-concentrating table, of a feed-box having feed openings or holes, and riffles arranged upon the upper surface of the table, that portion of the riffles lying opposite the feed-box increasing in height from a point opposite the feed hole or opening of the feed-box nearest the end of the table, said increase in height being in proportion to the number of feed holes or openings in the feed-box opposite which the riffles lie. 85

3. The combination with an ore-concentrating table, of a feed-box having feed holes or openings therein delivering upon such table, and riffles arranged upon the upper surface of said table, the portion of the riffles lying opposite the feed-box increasing in height, said riffles tapering or decreasing in height toward their other ends, as and for the purpose set forth. 90

4. The combination with an ore-concentrating table, means for reciprocating the same, and means for supplying the material to the table, of riffles arranged upon the upper surface of said table and extending generally in the direction of reciprocations imparted to the table, that portion of said riffles lying opposite the feed being of increasing height from the head toward the foot end of the table, the remaining portion of such riffles being of decreasing height. 95

5. The combination with an ore-concentrating table and means for imparting reciprocatory movements thereto, of a feed-box arranged adjacent to the head of the table, said table having an unriffled surface at its foot end, said riffles being of increasing height 100 from the head end of the table for the portion of the length thereof corresponding to the length of the feed-box and decreasing in height to the point of their termination upon said unriffled surface, as and for the purpose 105 set forth. 110

6. The combination with an ore-concentrating table, of a feed-box arranged to deliver the

material upon the surface of said table, and
rifles arranged upon the upper surface of
said table, said rifles being slightly spread
apart and of increasing height in the portion
5 of the length thereof lying opposite to and
corresponding to the length of said feed-box
and decreasing height toward the opposite
ends thereof, as and for the purpose set forth.

In witness whereof I have hereunto set my
hand, this 24th day of July, 1903, in the pres- 10
ence of the subscribing witnesses.
